BABY'S PLAY PEN

Robert H. Dawson, Longview, Wash.

Application March 15, 1950, Serial No. 149,661

6 Claims. (Cl. 5—99)

1

This invention relates to a two-sided play pen the primary object of which is to utilize a corner wall construction to form a substantially rectangular enclosed play area.

An important object of the invention is to provide a two-sided play pen of the character described which can be removably secured upon the walls of a corner construction and which may be folded against one to occupy a relatively small space when not in use.

A further object of the invention is to provide a play pen which is relatively simple in design and construction, cheap, portable, attractive in appearance, easy to manipulate, and especially adapted for use in small homes and apartments where space is a problem.

Yet another object of the invention is to provide in combination with a corner wall construction a foldable play pen comprising a pair of rectangular side members hinged together along a pair of corresponding vertical edges to form an inwardly foldable L-shaped frame, means for hingedly and removably securing the free vertical edge of one of said side members to one wall, and means for removably securing the free vertical edge of the other of said side members to the other wall whereby said L-shaped frame forms a rectangular play pen with said corner wall construction.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of the present pen shown assembled upon a corner wall construction;

Figure 2 is a sectional view taken on the line 2—2 of Figure 1;

Figure 3 is a vertical sectional view through the pen showing the same folded against a wall;

Figure 4 is a sectional view taken on the line 4—4 of Figure 1;

Figure 5 is a fragmentary perspective view of a portion of the pen illustrating the latching means; and,

Figure 6 is a perspective view of a four-sided movable pen formed from a pair of the two-sided pens shown in Figures 1—5.

Specific reference is now made to the drawings. In the several views in the accompanying drawings and in the following specification reference characters indicate corresponding elements throughout.

2

Indicated at 10 is a wall joined perpendicularly at 12 to a further wall 14 forming a conventional corner construction. The present play pen, which may be fabricated of suitable wood, plastics, aluminum or other light-weight metals, comprises a two-sided frame 16 which, when assembled, as shown in Figure 1, on the walls forms a rectangular play enclosure.

The pen includes two side members 18 and 20 each consisting of top and bottom bars or rails 22 and 24 joined by conventional rungs 26. The inner vertical end members or edges 28 and 30 are hinged together as at 32 in such a manner that the side member 18 is inwardly foldable in the direction of the arrow 34 (Figure 1). To assist in the folding operation, the bottom rail 24 of the side member 18 carries conventional caster wheels 36 adjacent its bottom corners. When the play pen is unfolded in the position shown in Figure 1, the free vertical end or edge 38 lies adjacent the wall 14 and is removably secured thereto by means of a hook 40 pivoted to the top rail 22 as at 42, the hook being removably received in an eye screw 44 secured in the wall 14.

The frame is removably and pivotally secured to the other wall 10 in the following manner. A bracket or block 46 is secured as by suitable screws 48 to the wall 10, the screws serving also to secure a plate 50 to the block. The plate is formed with spaced, open sleeves or female members 52. Secured to the vertical free end or edge member 54 of the side member 20 are spaced arcuate or L-shaped lugs or male members 56 which are rotatably and removably received in the sleeves or female members, the side member 20 being rotatable in the direction of the arrow 58 (Figure 1). Thus it will be seen that by unlatching the hook 40, rolling the side member 18 in the direction of the arrow 34 and then pivoting the side member 20 in the direction of the arrow 58, the pen may be folded against the wall 10.

To improve the utility of the play pen, a substantially rectangular base board 60 is hinged as at 62 for vertical movement on the wall 10. A suitable pad 64 may be tacked to the base board and a means is provided for retaining the base board in a horizontal position when the pen is unfolded, this means comprising pegs 66 pivoted as at 68 to the base board adjacent its free edge, the base board including recesses 70 for receiving the pegs when the latter are not in a supporting position.

The manner of folding the side members 55 against the wall 10 has been described herein-

above, and when the play pen is provided with a baseboard, the latter is first folded against the wall and then the side members are folded against each other and finally against the base board as shown clearly in Figure 3. A plastic covering 72 may be placed over the folded pen.

The present two-sided pen may be assembled into a four side movable pen as shown in Figure 6, it requiring two of the units described in connection with Figures 1-5. To accomplish this, the vertical end member 38 of each side member 18 will be provided with spaced lugs 56 while the vertical end members 46 of the side members 20 will be provided with spaced sleeves 52 (not shown in Figure 6). By making the vertical end members 46 correspond to the end members 38 and engaging the lugs 56 in corresponding sleeves 52, a four-sided movable pen such as shown in Figure 6 will be obtained.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In combination with a corner wall construction a foldable play pen comprising a pair of rectangular side members hinged together along a pair of corresponding vertical edges to form an inwardly foldable L-shaped frame, means for hingedly and removably securing the free vertical edge of one of said side members to one wall, and means for removably securing the free vertical edge of the other of said side members to the other wall whereby said L-shaped frame forms a rectangular play pen with said corner wall construction.

2. In combination with a corner wall construction a foldable play pen comprising a pair of rectangular side members hinged together along a pair of corresponding vertical edges to form an inwardly foldable L-shaped frame, means for hingedly and removably securing the free vertical edge of one of said side members to one wall, means for removably securing the free vertical edge of the other of said side members to the other wall whereby said L-shaped frame forms a rectangular play pen with said corner wall construction and a base board hinged for vertical movement on said one wall, said base board cooperating with said wall construction and said side members to form a floor support within said play pen.

3. The combination of claim 2 and casters carried by said other of said side members adjacent the free and hinged vertical edges thereof.

4. The combination of claim 3 and a means for supporting the base board in a horizontal position when the play pen is unfolded, said means including pegs pivoted to the bottom of said base board.

5. In combination with a corner wall construction a foldable play pen comprising a pair of rectangular side members hinged together along a pair of corresponding vertical edges to form an inwardly foldable L-shaped frame, means for hingedly and removably securing the free vertical edge of one of said side members to one wall, means for removably securing the free vertical edge of the other of said side members to the other wall whereby said L-shaped frame forms a rectangular play pen with said corner wall construction, said first-named means including a bracket secured to said one wall, spaced sleeves in said bracket, and spaced L-shaped lugs carried by said free vertical edge of said one side member removably receivable and horizontally rotatable in said sleeves.

6. In combination with a corner wall construction a foldable play pen comprising a pair of rectangular side members hinged together along a pair of corresponding vertical edges to form an inwardly foldable L-shaped frame, means for hingedly and removably securing the free vertical edge of one of said side members to one wall, means for removably securing the free vertical edge of the other of said side members to the other wall whereby said L-shaped frame forms a rectangular play pen with said corner wall construction, said last-named means including a hook pivoted to said other side member adjacent its vertical free edge and an eye keeper secured to said other wall removably receiving said hook.
